(57) CLAIM

The ornamental design for a cleaning satchel, as shown and described.

DESCRIPTION

FIG. 1 is a front perspective view of a cleaning satchel, in accordance with my new design.

FIG. 2 is a front view of the cleaning satchel, in accordance with my new design.

FIG. 3 is a left side cutaway view of the cleaning satchel, in accordance with my new design.

FIG. 4 is a right side cutaway view of the cleaning satchel, in accordance with my new design.

FIG. 5 is a rear view of the cleaning satchel, in accordance with my new design.

FIG. 6 is a top cutaway view inside the cleaning satchel, in accordance with my new design.

FIG. 7 is a top view of the cleaning satchel, in accordance with my new design; and,

FIG. 8 is a bottom view of the cleaning satchel, in accordance with my new design.

In the drawings, the broken lines indicate portions of the article not claimed or the unclaimed environment and form no part of the claimed design.

1 Claim, 7 Drawing Sheets
